OHIO.

FOCUSING DEVICE FOR AUTOMOBILE LAMPS.

Application filed October 9, 1925. Serial No. 61,555.

In the proper focusing of automobile lamps there are two essential adjustments required in order to place the lamp bulb filament in the focal center of the reflector. One of these 5 adjustments operates to move the lamp bulb forwardly and backwardly along a path axially of the reflector, while the other moves the bulb upwardly and downwardly to secure proper positioning thereof in a vertical direction. These two directions of movement are all that is required to obtain proper focal 10 adjustment of the bulb.

It is an object of our invention to produce a focusing device of extreme simplicity of 15 operation and construction to obtain these focusing movements, in which a minimum number of operating parts are employed, in which the operation of obtaining the required 20 adjustments is no more complicated than the operation of obtaining the usual forward and backward bulb adjustment, and in which the setting of one adjustment may be obtained independently of the other without disturbing 25 the adjustment of the cooperating adjustment means.

These and other objects are attained in the focusing device described in the following specification and illustrated in the accompanying drawing, in which:

Fig. 1 is a fragmental sectional elevation of portions of an automobile lamp equipped with a focusing device embodying our invention.

Fig. 2 is a fragmental rear elevation of the body of a lamp such as shown in Fig. 1.

Fig. 3 is a fragmental sectional view of the lamp shown in Fig. 1 and taken on the line 3—3 thereof.

Figs. 4, 5, 6, 7 and 8 are perspective views 40 of details of our invention, Figs. 6 and 7 embodying somewhat modified ideas of construction.

The style of lamp we have chosen to illustrate in disclosing an embodiment of our invention is provided with two main elements comprising a body 9 and a reflector 10. In the reflector we provide a vertically elongated aperture 11 in which a lamp bulb socket 12 is adapted to be moved vertically. This 50 socket may be provided with the usual extension 13 adapted to receive an adjustment screw 14 which has its slotted head 15 accessible from the outside of the lamp body. The usual spring 16 is provided to hold the socket

forwardly with the head of the screw 14 55 against the back of the body. Through this means the socket may be moved forwardly or backwardly to adjust the position of the bulb filament relatively to the focal center of the reflector, as is usual in bulb adjustment devices.

However, in addition to this forward and backward bulb adjustment device we have provided a novel mechanism for moving the 60 socket upwardly and downwardly in the aperture 11, which we will now describe. In the back of the lamp body 9 we form a slot 17 vertically so that the screw 14 may be moved vertically. On the inside of the body and against the inner wall thereof we mount a 70 pitman 18 which is pivoted on the screw 14, but which at its lower end is free to be moved in a circular motion so as to impart to the screw a vertical reciprocating movement in the slot 17. In order to accomplish this movement we provide a cam movement device at the lower end of the pitman. This device consists of a flange 19 turned outwardly about an annular opening 20 in the lower end of the pitman, over which and in cooperation with 75 which a cam cup 21 which has a flange 22, operates. In the cup 21 and in the body 9, in an off center position with relation to the cup 21, are formed openings for the reception of a pin 23 which is provided to rotate the cup. 80 The opening 24 in the body is circular to receive the circular portion 25 of the pin 23, while the opening 26 in the cup is square to receive the square portion 27 of the pin. The remainder 28 of the pin receives a spring 29, 85 a washer 30 and a cotter pin 31 through an aperture 32 in the end of the pin so that the cup or cam may be held in position over the flange of the pitman 18. The head 33 of the pin is slotted so that, just as in the case of 90 the screw 14, it may be rotated to adjusted positions by a screw driver applied from the back of the lamp. An escutcheon plate 34 is preferably applied to the back of the lamp body, a hole 35 being provided for the reception of the pin and a slot 36 being provided to cooperate with slot 17 in the body so that the screw may move therein during vertical adjustment. This plate is preferably 95 plated or polished so that the pin and screw 100 may be moved without marring the enamel or other finish of the body surface.

A feature to which we call attention in

Figs. 6 and 7 is a ratchet or locking provision consisting of a raised detent or ridge 37 which cooperates with teeth 38 formed on the edge of the cam flange 22 in locking the cam in adjusted positions of rotation. Thus the position of the pitman is rendered secure so that the screw 14 will remain in any position it may occupy in the slot 36. If the tension of spring 29 be made sufficient it will be found however that the cam will not move easily from its adjusted positions because there is sufficient friction between the parts to prevent displacement.

Another feature which may be embodied, although it has not been specifically illustrated, is some suitable mechanism adapted to secure more minute adjustment of the cam as for example by a gear and pinion interposed between the pin and cam. However, the minuteness of adjustment of the cam may be readily provided for by making the off center position of the pin 23 in the cam in accordance with the minuteness of adjustment desired, although such an expedient also results in varying the amount of throw of the cam and consequently the amount of movement which the lamp bulb socket may be given.

The operation of the focusing device we have just described is so simple and obvious from the foregoing description of its construction that specific description thereof is deemed unnecessary. The dotted line positions shown in Figs. 2 and 3 are self explanatory and the obvious cooperation of the notched or toothed cup 21 with the detent 37 of the pitman 18, as we have shown in Figs. 6 and 7, needs no description other than to point out that the spring 29 will operate to provide for yielding action of the cam cup as its notches pass from one to the other in cooperation with the detent, thus serving positively to lock the adjusted vertical position of the socket against displacement.

Having thus described our invention what we claim is:

1. A focusing device for automobile lamps having a slotted body and a reflector, consisting of a lamp socket, means connected with the socket and accessible for operation outside the lamp body, adapted to create a substantially axial adjustment movement of the

socket, and a second means accessible for operation outside the lamp body, adapted to create an adjustment movement of the socket in a direction substantially at a right angle to the axis of the lamp, said second mentioned means consisting of a pitman pivoted from and adapted to have swinging motion with relation to said first mentioned means, an eccentric connected with said pitman and having a fixed pivotal center on said body, and means pivoting the eccentric on the body, adapted to rotate the eccentric, whereby swinging movement of the pitman will move said first mentioned means in a direction substantially at a right angle to the axis of the lamp.

2. In combination with the slotted body and reflector of an automobile lamp, a focusing device consisting of a lamp socket extending into the reflector of the lamp, a focusing screw in the lamp body adapted when rotated to move the socket axially of the lamp, a pitman having pivotal movement at one end upon the focusing screw, said screw being mounted for movement in the body at a right angle to the axis of the screw, and an eccentric connected with the other end of the pitman, adapted when rotated to swing the pitman and to move its pivot end in the path of movement of and to carry with it the focusing screw at a right angle to the axis thereof.

3. In combination with the slotted body and reflector of an automobile lamp, a focusing device consisting of a lamp socket extending into the reflector of the lamp, a focusing screw in the slot of the body adapted when rotated to move the socket axially of the lamp, a pitman having pivotal connection at one end upon the focusing screw, said screw being mounted for movement in the slot of the body at right angles to the axis of the screw, and an eccentric connected with the other end of the pitman, adapted when rotated to swing the pitman and thereby to move the screw at its pivot end in the slot of the body, said screw and eccentric being accessible for operation outside the body.

In testimony whereof we have hereunto affixed our signatures.

THOMAS J. CORCORAN.
WILLIAM M. MATTEOLI.
